(57) **CLAIM**

The ornamental design for an electric skin brush applicator, as shown and described.

DESCRIPTION

FIG. 1 is an isometric view of the applicator showing the new design;

FIG. 2 is another isometric view of the applicator;

FIG. 3 is a side elevational view of the applicator, the other side being a mirror image thereof;

FIG. 4 is a top view of the applicator;

FIG. 5 is a bottom view of the applicator;

FIG. 6 is an elevational view of one end of the applicator; and,

FIG. 7 is an elevational view of an opposing end of the applicator.
